[57] CLAIM

The ornamental design for a bottle, substantially shown and described.

DESCRIPTION

FIG. 1 is a front elevational view of a bottle showing my new design, the opposite side being a mirror image of the side shown;

FIG. 2 is a top plan view thereof; and

FIG. 3 is a sectional view taken through line 3—3 of FIG. 1.

The sides not shown are the same in appearance as the sides shown.

FIG. 1

FIG. 2
